The ornamental design for an electrical receptacle tester, as shown and described.

DESCRIPTION

FIG. 1 is a front perspective view of an electrical receptacle tester according to our new and ornamental design;

FIG. 2 is a right side view thereof;

FIG. 3 is a left side view thereof;

FIG. 4 is front view thereof;

FIG. 5 is a rear view thereof;

FIG. 6 is top view thereof; and,

FIG. 7 is a bottom view thereof.

The evenly broken lines depict portions of the electrical receptacle tester that form no part of the claimed design. The dash-dot broken lines between the solid lines and the evenly dashed lines represent boundaries of the claimed design and form no part of the claimed design.
